(57) **CLAIM**

The ornamental design for a shower side spray, as shown and described.

DESCRIPTION

FIG. 1 is a perspective view of a shower side spray showing my design;

FIG. 2 is a front elevation view;

FIG. 3 is a rear elevation view;

FIG. 4 is a left side elevation view; wherein the right side elevation view is a mirror image thereof; and,

FIG. 5 is a top plan view; wherein the bottom plan view is a mirror image thereof.

The broken lines indicate portions of the shower side spray that form no part of the claimed design.
